Attorney.

UNITED STATES PATENT OFFICE.

GEORG MEIER, OF NUEREMBERG, GERMANY.

PENCIL WITH DISPLACEABLE GRAPHITE CORE.

Application filed May 27, 1921. Serial No. 473,043.

To all whom it may concern:

Be it known that I, GEORG MEIER, a citizen of the German Republic, and a resident of Nuremberg, Germany, have invented certain new and useful Improvements in Pencils with Displaceable Graphite Cores, of which the following is a specification.

This invention relates to a pencil having an inserted graphite core held in place by 10 a clamping mouthpiece and being adapted to be shoved forward by a displaceable stem located within the shell of the pencil. The lower end of the stem acts upon the upper end of the graphite core and causes the 15 lower end of this latter to project forth from the mouth-piece in order to be in writing position.

The difference between the novel construction forming the subject-matter of this invention and the known constructions consists in the feature that the front shell which contains the graphite core in its clamping head is supported by a spring with respect to the rear slidable shell which contains the 25 stem; the rear or upward motion of the slidable shell is limited by an abutment collar of the other shell against which the slid- able shell is pressed by said spring which is compressed, when the slidable shell is 30 displaced along the other shell in the direction towards the mouth piece, whereby the motion of the stem with respect to the graphite core is braked.

In this way an elastically influenced and 35 braked motion of the stem with respect to the graphite core is ensured and the latter is prevented from being entirely pushed through the mouth piece as frequently occurs with pencils with freely movable 40 graphite core which are operated by a non-braked stem. An always uniform length of the projecting graphite end is the more ensured as the upper shell returns automatically into its former position after each 45 actuation of the graphite core by the stem.

Another characteristic feature of the improved pencil consists in a longitudinally displaceable slotted clamping member arranged in the head of the pencil and receiving 50 the graphite core and forming the lower support for the above-mentioned spring, which presses the slotted member into the conical head of the lower shell whereby the graphite core is more securely 55 held in place. The spring has, thus, a two-

fold effect; it presses the two shells asunder, and improves the clamping action of the slotted member by making it co-act with the end of the respective shell. As the pressure of the spring is increased by shoving 60 the upper shell downward upon the lower one for the purpose of re-adjusting the graphite core, the slotted member is subjected also to an additional pressure and caused to act correspondingly stronger upon 65 the graphite core so as to warrant a practically positive re-adjustment of the graphite core whereby pushing this latter out of the mouth piece is entirely prevented, the more, as it is braked just during the readjustment. 70

The slotted clamping member offers also the advantage that the graphite cores may have unequal diameters and are still securely held in place, whereas the graphite cores used with the known constructions of 75 pencils of the kind in question must have the same diameter.

In order to make my invention more clear, I refer to the accompanying drawing, in which Fig. 1 is a longitudinal section 80 through a pencil constructed according to my invention; and Fig. 2 is a similar illustration, but partly in side-view, and showing the upper shell a little displaced upon the lower one in downward direction. 85

The pencil casing consists of the front shell 7 and the rear shell 1 which partly encompasses the former and may be displaced upon it for a certain length of way. The motion in that direction in which the pencil casing becomes longer is limited by a collar of the shell 7, as shown in Fig. 1. The outer end of the shell 7 contains an inserted member 8 which is slotted at 9 and may, if desired or preferred, be displaceable 90 in said shell. At the outer end of the member 8 is a bore which receives the graphite core 10.

The shell 1 contains the stem 5 which is secured by caps 3 and 4 affixed in their turn 100 in the upper end of said shell. The stem 5 lies axially within the shell 1 and its free end extends into the inner end of the bore of the inserted member 8. A spring 6 encompassing the stem 5 tends constantly to 105 move the two shells away from one another. The upper end of the spring abuts against the cap 3, the lower end abuts against the member 8.

The upper end of the shell 1 is closed by 110

a removable cap 2 which forms, together with the cap 4, a receptacle 11 for storing graphite cores.

When pressing upon the cap 2, the shell 5 1 is shoved downward along the shell 7 whereby the spring 6 is put under tension, or its pressure is increased respectively. At the same time, the stem 5 pushes upon the graphite core 10 and shoves it further outward (Fig. 2) so as to re-adjust its writing-end. Owing to the tension of the spring increasing when the shell 1 is displaced as just described, the braking action thereby produced counter-acts an eventual sudden push 15 upon the shell 1 and prevents the stem from pushing the core 10 out of the mouth of the shell 7.

If the inserted member 8 is longitudinally displaceable within the split end or 20 clamping mouth-piece 7^a of the shell 7, as it shall generally be the case (although it is not indispensably necessary), the increasing pressure arising on the spring 6 being compressed forces the outer end of the member 25 8 somewhat deeper into the outer end of the shell 7 whereby the graphite core is still better held in place. Owing to the two reasons, viz, the stronger hold of the core within the member 8 and the braking action of the spring with respect to the push cap 2, the core is very securely prevented from being unintentionally completely pushed out 30 of the shell mouth or casing mouth.

Having now described my invention, what 35 I claim as new and desire to secure by Letters Patent of the United States is:

1. A pencil, comprising, in combination, a

casing consisting of two shells adapted to be longitudinally displaced relatively to one another; a clamping mouth piece at the writing end of said casing; an exchangeable graphite core in said mouth piece; a stem located within the casing and being connected with the shell opposite to said mouth piece and adapted to shove said core outward; and a spring also arranged within the said casing between said shells and being adapted to move these latter away from one another, for the purpose set forth.

2. A pencil, comprising, in combination, 50 a casing consisting of two shells adapted to be longitudinally displaced relatively to one another; a clamping mouth piece at the writing end of said casing; an inserted slotted member situated near to said mouth piece; a longitudinal bore through said member, the outer part of said bore being adapted to receive an exchangeable graphite core; a stem located within the casing and being connected with the shell opposite to 55 said mouth piece and extending with its free end into the inner part of the bore of the said member; and a spring also arranged within the casing, between said shells, and abutting at one end against the 60 said member and at the other end against the adjacent shell, substantially as described.

In testimony whereof I affix my signature in presence of two witnesses.

GEORG MEIER.
